ABSTRACT OF THE DISCLOSURE

A building assembly made up of spaced inclined ramps extending at an acute angle to the horizontal and interconnected at their opposite ends by pairs of horizontally extending ramps.

This invention relates to a building that is adapted to contain a plurality of separate units and more particularly to an improved building construction that offers maximum space utilization.

The ever increasing land cost in urban areas has created an increased demand for buildings that offer a maximum degree of area utilization. Although multi-storied buildings provide this advantage, the buildings heretofore proposed result in the formation of cities without cultural or park areas. In addition, the previously proposed buildings do not offer the maximum potential for retail utilization wherein a plurality of different stores may be housed in one building.

It is, therefore, a principal object of this invention to provide an improved building that offers maximum space utilization without sacrifice of recreational or outdoor area.

It is a further object of the invention to provide a building that may serve a variety of functions.

There has been a recent trend toward shopping center areas in retail merchandising. The known type of shopping center normally spreads over vast areas and does not have any true continuity. The smaller retail stores are frequently positioned in less desirable traffic areas and thus cannot take advantage of the full traffic of the shopping area. In addition, the display areas of these out of the way stores, have no real value since there is insufficient traffic past them.

It is, therefore, a still further object of this invention to provide an improved building that may house a shopping center and in which maximum traffic flow will occur past each of the individual shopping units.

It is a still further object of the invention to provide an improved building that may be used for a shopping center and wherein the display areas of each of the units has maximum visibility.

A building embodying this invention is adapted to house a plurality of separate units. The building is comprised of a first series of inclined ramps that extend substantially parallel to each other and are inclined at an acute angle to the horizontal. A second series of inclined ramps is spaced laterally from the first series and is comprised of parallelly extending ramps disposed at an acute angle to the horizontal. The inclined ramps of each series are connected at one end of the building by a series of connecting levels and are connected at the opposite building end by a second series of connecting levels.

Other objects and advantages of the invention will become more apparent as this description proceeds, particularly when considered in conjunction with the accompanying drawings, wherein:

FIGURE 1 is a perspective view of a building embodying this invention;

FIGURE 2 is a partial cross sectional view taken generally along the line 2—2 in FIGURE 1;

2

FIGURE 3 is a cross sectional view taken along the line 3—3 in FIGURE 2;

FIGURE 4 is an enlarged cross sectional view taken generally along the line 4—4 in FIGURE 1;

FIGURE 5 is a perspective view showing the mall area of the building on a larger scale;

FIGURE 6 is a schematic view illustrating the interrelation between the various levels of the building shown in FIGURES 1 through 5; and

FIGURE 7 is a schematic view, in part similar to FIGURE 6, showing another embodiment of the invention.

Referring now in detail to the drawings and in particular to the embodiment in FIGURES 1 through 6, a building embodying this invention is indicated generally by the reference numeral 11. The building to be described is a shopping or retail center, but it is to be understood that it may house other types of separate units. For example, the building 11 may house residential units, professional offices, or may be made up of a mixture of residential, office and retail units.

The floor layout of the building 11 may be best understood by reference to FIGURE 6 wherein the various floor levels are illustrated schematically. The floor levels are made up of a first series of inclined ramps 12, 13 and 14 that are parallel to each other and extend at a small acute angle with respect to the horizontal. The ramps 12, 13 and 14 extend upwardly from one end of the building and lie at an angle that is preferably no greater than about 5° to the horizontal. In a preferred embodiment of the invention, the ramps 12, 13 and 14 lie at a 2° angle to the horizontal. The reason for the small acute angle will become more apparent as this description proceeds.

Spaced laterally from the inclined ramps 12, 13 and 14 is a second series of inclined ramps 15, 16 and 17 that extend upwardly from the opposite end of the building. The ramps 15, 16 and 17 also are disposed in parallel relationship with respect to each other at an acute angle to the horizontal. Preferably, the angle of the ramps 15, 16 and 17 is equal to the angle of the ramps 12, 13 and 14.

A first series of connecting levels 18, 19 and 21 is formed at the end of the building from which the ramps 12, 13 and 14 ascend. The connecting levels 18, 19 and 21 are preferably parallel to each other and extend substantially parallel to the horizontal plane. One end of the ramps 13 and 14 are integrally connected to the connecting levels 18 and 19, respectively. The adjacent ends of the ramps 15, 16 and 17 are connected to the opposite end of the connecting levels 18, 19 and 21, respectively. Thus, the connecting levels 18, 19 and 21 provide a horizontal connection between the adjacent ends of the inclined series of ramps.

At the opposite end of the building, a second series of connecting levels 22, 23 and 24 is provided. The connecting levels 22, 23 and 24 are parallel to each other and substantially parallel to the horizontal. One end of the connecting levels 22, 23 and 24 is connected to the upper ends of the inclined ramps 12, 13 and 14. The other end of each connecting level is connected to the lower ends of the inclined ramps 15, 16 and 17. The connecting levels 22, 23 and 24, therefore, provide access between adjacent ends of the series of inclined ramps at the respective end of building 11.

The connecting levels 18, 19 and 21 are spaced a considerable longitudinal distance from the connecting levels 22, 23 and 24, as has been noted, and the inclined ramps 12, 13 and 14 are spaced laterally from the inclined ramps 15, 16 and 17. This spacing provides an open air mall area, indicated generally by the reference numeral 25, in the center of the building. This mall area is shown in more detail in FIGURE 5.

Vertically extending walls 26 and 27 are formed on each series of the inclined ramps spaced inwardly from the mall to form the outer surfaces of units which may function as stores, office spaces, or living areas on each inclined ramp. The inward spacing of the walls 26 and 27 provides sidewalks or walkways, indicated generally by the reference numeral 28, on the side of each ramp adjacent the mall 25. Intermediate the ends of the inclined ramps 12-17, transversely extending connecting ramps 29 are provided that connect the center of each of ascending ramps at one side of the building with the center of the next lower descending ramps at the other side of the building. Adjacent the ramps 29 are formed transverse extending ramps 31 that connect each of the inclined ramps at one side of the building with the next higher adjacent ramp at inclined at the other side of the building.

The outer walls 26 and 27 coat with vertically extending walls 32 on each of the inclined ramps to provide individual units, as indicated generally by the reference numeral 33. As has been noted, the units 33 may be stores, office spaces or living areas. It will be noted from FIGURE 5 that the facing walls 26 and 27 provide a coextensive display area that may be viewed conveniently from any level so that substantially all of the stores within the building 11 may be viewed from any place therein.

Although the floor of each of the units 33 is inclined slightly due to the incline of the ramps 12, 13, 14, 15, 16 and 17, the incline is not sufficient to become noticeably objectionable to occupants of the units 33. If, however, it is desired to provide a completely level floor in any of the units, the floor may be provided with appropriate overlay that will provide the desired horizontal surface.

The connecting levels 18, 19, 21, 22, 23 and 24 are also divided into units 34 which may be utilized for any desired purpose such as stores. The units 34 have outer walls 35 that are spaced inwardly from the mall 25 so as to provide a walkway or sidewalk 36 in front of the units 34. The sidewalks 36 are connected to the sidewalks 28 to provide a continuous generally spiral sidewalk area around the mall 25. It should be readily apparent, particularly by reference to FIGURE 6, that a person entering the building 11 may walk up the inclined ramp 12 to the first connecting level 22 and then to the second inclined ramp 15 and thus in a somewhat screw threaded manner around the building 11 until the uppermost level is reached. Due to the relatively gradual angle of the inclined ramps 12, 13, 14, 15, 16 and 17, the persons will not notice their gradual ascent. Thus, it should be readily apparent that the traffic pattern in the building 11 causes maximum exposure to all of the store units contained therein. The connecting ramps 29 and 21 can be utilized, however, to facilitate crossing over between the inclined ramps if desired and, elevators (not shown) may interconnect the various ramps or connecting levels.

In the embodiment just described, all of the inclined ramps are of uniform width and thus a generally rectangular exterior shaped building is provided. If residential or urban renewal area is desired, an exposed sun deck or yard may be provided on each floor by making the ramps of decreasing width progressing toward the top of the building. Such an embodiment is shown in FIGURE 7.

In the embodiment in FIGURE 7, a first series of inclined ramps 51, 52, 53 and 54 extend at a small acute angle to the horizontal. Oppositely extending ramps are provided on the opposite side of the building. The inclined ramps are joined by connecting levels 55, 56, 57, 58 and 59 at one end of the building and connecting levels 61, 62, 63 and 64 at the other end of the building. It will be noted that inclined ramps 51 through 54 decrease in width to ward the top of the building so that a portion of their outer periphery will be exposed to give a sun deck area thereto. Of course, it would be possible to alter the width inwardly so that a mall of increasing width were providing along the height of the building. If desired, a more conventional multi-story structure, indicated generally by the

reference numeral 65, may replace the mall of the previous embodiment. In all regards the building shown schematically in FIGURE 7 may be considered the same as that in FIGURES 1-5.

It is to be understood that the specific construction of the improved building herein disclosed and described is presented for the purpose of explanation and illustration and is not intended to indicate limits of the invention.

What is claimed is:

1. A building adapted to house a plurality of separate units comprising a first series of inclined ramps extending substantially parallel to each other and being inclined at an acute angle to the horizontal, said first series of inclined ramps extending upwardly from one end of said building, a second series of inclined ramps extending upwardly from the other end of said building, said second series of ramps extending substantially parallel to each other and being inclined at an acute angle to the horizontal, said first and second series of inclined ramps being spaced laterally from each other to define a substantially open mall therebetween, a first series of parallel horizontally extending connecting levels at one end of said building, each of said first series of connecting levels being connected at one end thereof to one of said first series of inclined ramps and being connected at its other end to one of said second series of inclined ramps, a second series of parallel horizontally extending connecting levels at the other end of said building, each of said second series of connecting levels being connected at one end thereof to one of said first series of inclined ramps and being connected at its other end to one of said second series of connecting levels, said first and second series of connecting levels being longitudinally spaced from each other to define the longitudinal ends of said mall, said ramps and said connecting levels defining a floor surface of a generally spiral shape consisting of a ramp of the first series terminating at one end of a connecting level of the first series, the connecting level of the first series terminating at its other end at one end of a ramp of the second series, the other end of the ramp of the second series terminating at one end of a connecting level of the second series, the other end of the connecting level of the second series terminating at one end of a ramp of the first series and so on, and means providing a plurality of units upon each of said inclined ramps.

2. A building as set forth in claim 1 wherein a plurality of interconnecting ramps extend between the first and second series of inclined ramps, each of said interconnecting ramps being connected at one end thereof to one of said first series of inclined ramps and at its other to one of said second series of inclined ramps, said interconnecting ramps being spaced between the connecting levels and extending across said mall.

3. A building as set forth in claim 1 wherein means provide units on each of the connecting levels and the units are spaced outwardly from the mall to provide a walking area between said units and said mall on said connecting levels.

4. A building as set forth in claim 1 wherein the means providing the units upon the inclined ramps are spaced outwardly of the mall to provide a walkway between said units and said mall on each of said ramps.

5. A building as set forth in claim 4 wherein each of the inclined ramps extends at an angle no greater than 5° to the horizontal.

6. A building as set forth in claim 4 wherein each of the inclined ramps extends at an angle substantially equal to 2° to the horizontal.

7. A building as set forth in claim 1 wherein the inclined ramps of each series of inclined ramps extend laterally beyond the next uppermost inclined ramp in the respective series to provide an exposed area at the periphery of each of said inclined ramps.

8. A building adapted to house a plurality of separate units comprising a first series of ramps extending upwardly from one end of said building, said first series

of ramps extending substantially parallel to each other and being inclined at an acute angle to the horizontal, a second series of ramps extending upwardly from the other end of said building, said second series of ramps extending substantially parallel to each other and being inclined at an acute angle to the horizontal, said first and second series of inclined ramps being spaced laterally from each other, a first series of connecting levels at one end of said building, said first series of connecting levels extending substantially parallel to each other and being substantially parallel to the horizontal, each of said first series of connecting levels being connected at one end thereof to one of said first series of inclined ramps and being connected at its other end to one of said second series of inclined ramps, and a second series of connecting levels at the other end of said building, said second series of connecting levels extending substantially parallel to each other and to the horizontal, each of said second series of connecting levels being connected at one end thereof to one of said first series of inclined ramps and being connected at its other end to one of said second series of inclined ramps, said ramps and said connecting levels defining a floor surface of a generally spiral shape consisting of a ramp of the first series terminating at one end of a connecting level of the first 25 series, the connecting level of the first series terminating at its other end at one end of a ramp of the second series, the other end of the ramp of the second series termini-

nating at one end of a connecting level of the second series, the other end of the connecting level of the second series terminating at one end of a ramp of the first series and so on.

5 9. A building as set forth in claim 8 wherein each of the inclined ramps extends at an angle no greater than 5° to the horizontal.

10 10. A building as set forth in claim 8 wherein each of the inclined ramps extends at an angle substantially equal to 2° to the horizontal.

15 11. A building as set forth in claim 8 wherein the inclined ramps of each series of inclined ramps extend laterally beyond the next uppermost inclined ramp in the respective series to provide an exposed area at the periphery of each of said inclined ramps.
